BUILDING STRUCTURES
Andrew Sundquist, Denver, Colo.
Application August 2, 1955, Serial No. 525,850
2 Claims. (Cl. 40—125)

2

Figure 8 is a fragmentary sectional view taken along the line 8—8 of Fig. 7;

Figure 9 is a sectional view of a modified form of numerical indicia and supporting molding constructed according to the present invention;

Figure 10 is an enlarged fragmentary sectional view taken along the line 10—10 of Fig. 8;

Figure 11 is a fragmentary sectional view taken along the line 11—11 of Figure 9;

Figure 12 is a fragmentary sectional view showing still another modified form of the numerical indicia and supporting molding of the present invention, shown supported on a solid door structure; and

Figure 13 is an enlarged fragmentary sectional view showing the modified form of the molding structure of Fig. 12 supported on a paneled door.

Referring more particularly to the drawing, there is shown in Fig. 1 an opaque building section, generally designated by the reference number 11 and illustrated as 15 a door having its outer face 12 visually observable and having its inner face 13 disposed interiorly of the building. The building structure 11 may be the solid door illustrated in Figure 1, the paneled door illustrated in Figure 2, or the transom illustrated in Fig. 3.

The building section 11 is provided with cutouts extending transversely therethrough from the outer face 12 toward and terminating in the inner face 13 and shaped complementary to indicia to be supported therein, the 20 cutouts being generally designated by the reference number 14. The cutouts 14 are shaped to generally conform to the outline of house-identifying numbers, the outlines being selected to ornamenteally and attractively adorn the building section 11.

Engaged against the bounding wall of each of the cutouts 14 is a molding 15 which is detachably secured within the cutouts by means of the securing elements 16, Fig. 4. Each of the moldings 15 includes a bead 17 abutting against the outer face 12 of the opaque house section 11, and outlining the adjacent one of the indicia during the daytime. Contiguous to and spaced from the bead 17, the inner face 18 of the molding 15 is provided with a continuous slot 19 for the support of the indicia 20 which are fabricated of a transparent material and bridge each of the cutouts 14. It is to be noted that each of the beads 17 has its exposed face provided with a luminous coating to thereby outline the indicia 20 during the night. Accordingly, the indicia 20 are supported in a manner wherein light from the interior of the house passes through the indicia, and the opaque bounding portions of the door 25 or transom clearly outline the indicia 20. Also, the indicia can be readily observed during the day, as well as in the night.

It is to be noted that the indicia may be colored to further enhance the ornamental appearance of the structure of the present invention, and further, the indicia can be shaped to simulate different emblems, such as a cross, heart and clover leaf, human outlines of figures, and so forth.

In Figures 4 to 6, inclusive, there is shown one form 60 of the molding 15 for supporting the indicia 20. In this form the molding has one end terminating contiguous to the inner face 13 of the building section 11, and has other end terminating contiguous to the outer face 12 of the building structure and merging into the bead 17. The 65 inner face 18 of the molding 15 tapers inwardly from the end contiguous to the inner face 13 of the building section 11 toward and terminating in the molding 17. As previously pointed out, the indicia 20 is supported within the slot 19 provided contiguous to and spaced inwardly of the bead 17, the spacing being selected so that the outer face of the indicia 20 is in substantial alignment with the outer face 12 of the building section 11.

This invention relates to building structures, and more particularly to devices for visually displaying house-identifying indicia.

Reference is hereby made to applicants' prior invention set forth in an application filed August 25, 1950, and bearing Serial Number 181,409, now abandoned.

An object of this invention is to provide a novel structure for visually displaying house numbers during the day as well as the night.

Another object of this invention is to provide an opaque door or transom structure which is adapted to receive and support transparent indicia in a manner wherein light from the interior of the house passes through the indicia, and the opaque bounding portions of the door transom clearly outline the indicia.

A further object of this invention is to provide supporting means for holding numerical indicia within complementary apertures provided in a door or transom.

A still further object of this invention is to provide a novel structure for displaying ornamental, transparent indicia on a portion of a dwelling house or building, the indicia being readily seen at a relatively great distance during the day as well as at night.

A still further object of this invention is to provide a novel structure for visually displaying house numbers, which is relatively simple in structure and cheap to manufacture.

The above and still further objects and advantages of the invention will become apparent upon consideration, and with the foregoing and other objects in view, all of which more fully hereinafter appear, the invention comprises certain novel construction, combinations and arrangements of parts and elements as hereinafter described and as defined in the appended claims and illustrated in preferred embodiment in the accompanying drawings, in which:

Figure 1 is a front elevational view of a solid door structure constructed according to the present invention, for visually displaying house-identifying indicia;

Figure 2 is a fragmentary front elevational view of a paneled door structure constructed according to the present invention, for visually displaying house-identifying indicia;

Figure 3 is a front elevational view of a transom structure constructed according to the present invention for visually displaying house-identifying indicia;

Figure 4 is an enlarged fragmentary sectional view, with parts broken away, taken along the line 4—4 of Fig. 1;

Figure 5 is a front elevational view of one of the numerical indicia utilized in conjunction with the structure shown in Figs. 1 to 3 inclusive;

Figure 6 is a fragmentary sectional view taken along the line 6—6 of Fig. 5;

Figure 7 is a front elevational view of another numerical indicia used in conjunction with the structure shown in Figs. 1 to 3 inclusive;

3

In Figures 7, 8 and 10, there is shown a modified form of the molding for supporting the indicia 20 within the building section 11 having the outer face 12 and the inner face 13, the modified form being designated by the reference numeral 30. The molding 30 has one end 31 terminating adjacent the inner face 13 of the building section 11 and has the other end terminating in a bead 32 abutting against the outer face 12 of the opaque building section 11. The outer face of the molding 30 engages against the adjacent portions of the cutouts 14 and the inner face includes a pair of inclined surfaces 33 and 34 which converge inwardly from the ends of the molding and terminate in a centrally disposed, continuous slot 35 provided interiorly of the molding 30. The slot 35 receives the indicia 20 and supports the latter in bridging relation with respect to the molding in a position substantially midway between the inner and outer faces of the building section 11.

In Figures 9 and 11, there is shown another modified form of the molding for supporting the transparent indicia 20, this modified form being designated by the reference numeral 40. The molding 40 has one end terminating contiguous to the inner face 13 of the building section 11, and has the other end terminating in a molding 41 overlying and abutting against the outer face of the opaque building section 11. The securement of the molding within the cutout 14 is effected by the securing elements 42, illustrated as brads or nails. The inner face of the molding includes a pair of arcuate surfaces 43 and 44 which converge upwardly and inwardly to terminate in a centrally disposed, continuous slot 45 for the support therein of the numerical indicia 20. Accordingly, the numerical indicia 20 is supported substantially midway between the inner and outer faces of the building section 11. In Figure 12, there is shown still another modified form of the molding for supporting the numerical indicia 20, this form being designated by the reference numeral 50. The molding 50 includes the bead 51 abutting against the outer face 12 of the building section 11, the molding being secured in place by means of the brads or nails 52 which extend through the molding and engage within the solid door illustrated in Figure 12. The inner face of the molding 50 includes a pair of concave surfaces 53 and 54 which converge upwardly and inwardly of the outer ends of the molding and terminate in a continuous slot 55 for the support therein of the marginal edges of the numerical indicia 20.

In Figure 13, there is shown the molding 50 supported on a building section 11, shown in the form of a paneled door having an outer panel 56 and an inner panel 57 carried by the supporting block 58. The molding 50 is supported with its bead 51 overlying the outer panel 56 and with the outer face of the molding abutting against and engaging the adjacent portions of the filler block 58 of the door. The molding 50 is secured in place by means of a wood screw or the like, designated by the reference numeral 57'. The transparent numerical indicia 20 are supported within the slot 55 of the molding substantially

midway between the inner and outer panels 56 and 57 of the door.

From the foregoing, it is readily apparent that the present invention contemplates a structure wherein transparent windows are employed to provide visually observable house numbers. These numbers can be readily seen during the day as well as during the night, and may be manufactured separately to be placed in panels of old doors already installed and into new doors to be installed, and also into panels in transoms over doors. Further, if desired, these door structures can be fabricated, during manufacture, to receive the molding and identifying indicia of the present invention.

While I have described many details and constructions it is obvious that others skilled in the art can devise alternate and equivalent constructions within the scope and spirit of the invention and hence I desire that my protection be limited only by the proper scope of the appended claims.

I claim:

1. A device for displaying indicia on a building comprising an opaque building section having its outer face visually observable and having its inner face disposed interiorly of said building, said building section being provided with a cut out extending transversely therethrough from said outer face to and terminating in said inner face and shaped to conform to an indicia to be displayed, a hollow open ended molding conformably shaped to correspond to and be received within said cut out position within said cut out, said molding extending from the outer face to the inner face of said building section, a bead extending about the open end of said molding adjacent the outer face of said building section and abutting against the latter named face, there being a slot extending about the inner face of said molding inwardly of said bead, and an indicia fabricated of a transparent material bridging said molding and supported in said slot.

2. A device for displaying indicia on a building comprising an opaque building section having its outer face visually observable and having its inner face disposed interiorly of said building, said building section being provided with a cut out extending transversely therethrough from said outer face to and terminating in said inner face and shaped to conform to an indicia to be displayed, a hollow open ended molding conformably shaped to correspond to and be received within said cut out positioned within said cut out, said molding extending from the outer face to the inner face of said building section, a bead extending about the open end of said molding adjacent the outer face of said building section and abutting against the latter named face, there being a slot extending about the inner face of said molding inwardly of said bead, an indicia fabricated of a transparent material bridging said molding and supported in said slot, and securing elements extending through said molding intermediate its open ends and the adjacent portion of said building section for holding the molding in place within the cut out.
